CIRCUIT INTERRUPTER

John B. MacNeill, Wilkinsburg, Benjamin P. Baker, Turtle Creek, and Andrew H. Bakken, Edgewood, Pa., assignors to Westinghouse Electric & Manufacturing Company, East Pittsburgh, Pa., a corporation of Pennsylvania

Application January 11, 1940, Serial No. 313,430

12 Claims. (Cl. 200—148)

This invention relates to improvements in circuit interrupting apparatus and, more particularly, to circuit interrupters of the dry type using a blast of air or other gas to extinguish the arc drawn between separable contacts and to operating means therefor which are in certain aspects also adapted to circuit interrupters other than the air blast type.

It is now the general practice to house circuit interrupting apparatus for indoor use in cells or metal cubicles in order to provide a high degree of safety to operators and adjoining apparatus. Heretofore, the oil circuit breaker was almost universally used in installations of this kind. However, due to the fire hazard accompanying oil breakers, power companies have given more and more consideration to oilless breakers and particularly breakers of the air break type. Circuit breakers employing a blast of compressed air to extinguish the arc have been developed which have an interrupting capacity comparable to that of oil circuit breakers in the same voltage class.

It is an object of our invention to provide a compressed air breaker structure that is compact in design, simple and rugged in construction and which will readily adapt itself to mounting in spaces such as cells or cubicles formerly housing oil circuit breaker equipment.

It is the usual practice in the operation of a plurality of compressed air breaker units to provide a central compressed air system feeding the individual units. In order to insure reliability of operation, each unit is provided with a separate or auxiliary pressure tank of capacity sufficient to operate the individual breaker at least once in the event the main or central supply of air is made unavailable. Our invention contemplates using the auxiliary pressure tank as a support upon which the circuit interrupting elements and operating mechanism are mounted, thereby affecting economy in space required to house the breaker.

A more specific object of our invention is to provide a circuit breaker with the pressure tank and the operating and control mechanism grouped as a unit all at ground potential with the contacts and arc chamber supported on the tank by means of insulating material which includes an insulating conduit for conducting gas from the tank to the arc chamber.

A further object of our invention resides in the provision of a simplified moving contact structure for a polyphase circuit breaker and proposes uniting the moving contact members in a single unitary structure including a single fluid pressure operated piston for moving the contact members to open and closed circuit positions.

It is also an object of our invention to provide an improved control system applicable for controlling in proper sequence the opening and clos-

ing operation of a gas blast breaker and the admission of an arc extinguishing blast of gas to the breaker arc extinguishing means.

It is an object of our invention to provide an improved circuit breaker and operating mechanism having a piston for operating the contacts to open and closed positions when pressure is admitted to opposite sides of the piston, with means automatically operable when the contacts reach closed position to hold them closed against any opening force applied to the contacts and arranged so that the application of pressure to the opening side of the piston causes the contacts to be moved to open position.

A further object of our invention is directed to control means for a gas pressure actuated operating mechanism for gas blast interrupters which prevents actuation of the contact mechanism if there is insufficient gas pressure available to move the contacts promptly to the open or to the closing position and if the gas pressure is insufficient to extinguish the arc.

Our invention also has for its object the improvement of the opening operation of gas pressure actuated operating mechanisms by holding the contact structure in the closed position until substantially full operating pressure has been applied to the gas pressure operated piston and thereafter releasing the contact structure so as to obtain opening movement of the contact structure with a snap action.

Other objects and advantages will be apparent from the following description when read in connection with the accompanying drawings, in which:

Figure 1 is a front elevational view of a circuit interrupter illustrating our invention;

Fig. 2 is a side elevational view of the interrupter shown in Fig. 1;

Fig. 3 is a schematic illustration of the operating mechanism of our circuit interrupter and the control system therefor; and

Fig. 4 is a schematic development of the auxiliary switch used in the control system of our invention, showing the relative positions of the contact structure for both the open and closed positions of the circuit interrupter.

Referring to the drawings, the reference numeral 5 designates a pressure tank for storing gas, such as air, which is preferably supplied from a central source of pressure, not shown. Secured to the upper side of the tank 5 is a framework composed of transverse bars 7 joined by longitudinal extending support bars 9, 11, 13 and 15. Secured to the bars 9 and 11 and disposed in spaced relation therealong are three insulators 17. Three insulators 19 of slightly greater length are similarly arranged and supported upon the bars 13 and 15. The insulators 17 and 19 are grouped in pairs and provide the support for three

identical circuit interrupting units generally indicated at 21. Each circuit interrupting unit 21 comprises a stationary contact assembly 23 and a coacting movable contact 25. The contacts 23 and 25 when in the closed circuit position are surrounded by an arc chute 27 of insulating material. The moving contacts 25 are preferably of blade-like construction and operate into and out of engagement with the stationary contacts 23 through a relatively narrow throat-like portion 29 of the arc chute 27. Each contact blade 25 is guided in its reciprocating movement by a support arm 31 mounted upon the insulator 19. The support arms 31 are provided with yielding contact fingers 33 which bear on opposite sides of the contact blade 25 so as to establish a good electrical connection between the blade and the support.

The support arms 31, therefore, also serve as a current conductor and are provided with a terminal 35 to which an external circuit connection can be made. The stationary contacts 23 are each provided with a terminal connector 37 to which the other external circuit connection can be made. Thus the electrical circuit through each circuit interrupting unit 21 proceeds from the external terminal 37, stationary contact 23, moving contact blade 25, contact fingers 33, guide bracket 31 and terminates at the terminal 35. Each of the moving contacts 25 is secured at its lower end to an insulator 39 which, in turn, are rigidly mounted at their lower ends to a transversely extending beam 41. The beam 41 is provided with an operating rod 43 associated with a piston 45 movable in an air actuated operating cylinder 47 which is preferably supported from a bracket 49 secured to the side of the pressure tank 5. It will thus be seen that by reciprocating the piston 45, the moving contacts 25 will be moved to open and closed circuit position as a unit. In the full open circuit position the moving contacts 25, as shown by dotted line position 25a in Fig. 2, are completely removed from the arc chutes 27 to provide visible air gaps between the upper ends of the contacts and the air chutes.

In order to arrest the motion of the moving contact assembly at the end of either its opening or closing stroke, shock absorbers, as shown at 46-48 and 48-48, are provided. For example, the shock absorbers 46 are adapted to engage the beam 41 at the end of the opening stroke whereas the shock absorbers 48 arrest the motion of the beam 41 on the end of the closing stroke.

Operation of the piston 45 to the open circuit position is accomplished by the admission of air under pressure from tank 5 through a control valve 51. The control valve 51 is connected with the pressure tank 5 through a conduit 53 and connects with the cylinder 47 by way of conduit 55. Closing movement of the movable contact 25 is accomplished by admitting air under pressure from the tank 5 through the control valve 57. The control valve 57 is similar to the valve 51 and connects with the pressure tank 5 through a conduit 59 and delivers air under pressure to cylinder 47 through the conduit 61. An arc established between the stationary contact 23 and the moving contact 25 is adapted to be extinguished by a blast of gas delivered from the pressure tank 5 to the arc chute 27. For this purpose, an air blast valve 63 is supported by and connected to the tank 5 by a connection 65. The valve 63 is connected to an outlet pipe 67 which connects with a manifold 69 having three outlet branches terminating, respectively, at the base of each insulator 19. The insulators 19 are of

cylindrical construction and provide a passage 71 through which air from the valve 63 may be directed to the arc chutes 27. Each of the throat-like portions 29 through which the moving contacts 25 operate communicate with a passage 73 which, in turn, is arranged to form a coextensive passage with the opening 11 in the insulators 19. It is thus seen that upon opening of the valve 63 at a time when an arc is drawn between the contacts 23 and 25, a blast of gas from the tank 5 will pass through the valve 63, the conductor 67, manifold 69, the three passages 71 to the respective arc chutes 27 where the three individual blasts are deflected to pass crosswise of the arc between the contacts 23 and 25 thereby causing the arcs to be extinguished.

The valves 51, 57 and 63 are preferably controlled by electromagnetically actuated pilot valves 75, 77 and 79, respectively. The operation of the pilot valves 75, 77 and 79 are controlled by an auxiliary switch 81 suspended from the support bars 9 and 11. The auxiliary switch 81 is provided with an actuating arm 83 operatively coupled to the beam 41 at 85. Further details of the auxiliary switch 81 and the operation thereof in controlling the circuit interrupter will appear hereinafter in connection with a description of the control system.

In order to operate the circuit interrupter to open and closed positions, a control system has been devised, as more clearly shown in Fig. 3. It will, of course be understood that the illustration in Fig. 3 is merely schematic for the purpose of clarifying the operation and function of the apparatus.

With particular reference to Fig. 3, the pilot valves 75, 77 and 79 are provided, respectively, with actuating coils 87, 89 and 91. These coils are adapted to be energized from a suitable source of electrical potential indicated by the conductors 92 and 93. One terminal of each coil 87, 89 and 91 is connected by a conductor 95 to the potential source 92. The other side of coil 87 is connected by conductor 97 through terminals b-a of the auxiliary switch 81 to conductor 99. Connection from the conductor 99 to the conductor 93 of the source may be made either through the conductors 101 and 103 through the relay 105 or through the conductors 107 and 109 through the push-button switch 111. The actuating coil 89 for controlling the pilot valve 77 is connected by means of conductor 113 through the terminals d-c of the auxiliary switch 41, conductor 115 to the push-button switch 111 and finally through conductor 109 to the conductor 93 of the source of control potential. The actuating coil 91 of the pilot valve 79 is connected by conductor 117 through the terminals f-e of the auxiliary switch 81 and conductor 119 to the line 93 of the control potential source.

The auxiliary switch 81 is of the usual construction having a rotatable drum, not shown, carried by the shaft 121 which, in turn, supports the actuating arm 83 pivotally coupled to the moving contact structure at 85. The rotatable drum within the switch 81 carries a plurality of contact segments schematically shown in Fig. 4. For example, when the circuit interrupter is in the closed circuit position, the auxiliary switch takes a position such that a pair of connected contact segments 123 on the drum bridge the terminals a and b. A pair of segments 125 are out of contacting engagement with the terminals c and d. The contact segments 127 and 129 are also out of contacting engagement respectively

with terminals *e-f* and *g-h* whereas the segments 131 are in bridging relation with respect to the terminals *i-j*.

Fig. 4 also illustrates the position of the bridging contact segments on the drum of the auxiliary switch 81 when the breaker is in the open position. In moving from the closed to the open position, the segments 123 will have passed over the terminals *a-b* and come to rest out of engagement with these terminals. The segments 125 will have moved from a position out of engagement to engaging position with respect to terminals *c-d*. The segments 127 will have moved from a position out of engagement to one of engagement and finally take a position out of engagement with the terminals *e-f*. The segments 129 will have moved from a position normally out of engagement to one of bridging engagement with the terminals *g-h* whereas the bridging segments 131 will have moved from a position of engagement to one out of engagement with the terminals *i-j*.

As shown in Fig. 3, the movable contact members 25 are in the open circuit position. In order to effect a closing of the interrupter contacts by manual control, the control button 133 of the push-button switch 111 is depressed so as to complete the circuit from conductor 93, conductor 109 to the conductor 115, terminals *c-d* of the auxiliary switch 81 which, for the open circuit position of the breaker, are bridged by the segments 125, the conductor 113, coil 89 of the pilot valve 77, and back to the source of control potential through the conductor 95. It will be noted that for this position of the auxiliary switch, the terminals *a-b* in circuit with the coil 87 as well as the terminals *e-f* in circuit with the coil 91 are in open circuit position. Upon energization of the coil 89, the pilot valve 77 is opened, admitting air under pressure from the tank 5 to the upper end of the control valve 51 which causes the valve to open and admit air through conductor 61 to the lower end of the operating cylinder 47. The air thus admitted reacts against the piston 45, driving it upwardly so as to actuate the rod 43 and the beam 41 carrying the contact members 25 to the closed circuit position.

It will be noted that as the moving contact assembly moves toward the closed circuit position, the auxiliary switch 81 is also moved towards the closed position and that when the closed circuit position has been reached, the terminal *c-d* of the auxiliary switch will no longer be bridged by the segments 125 and the control circuit to the coil 89 will be opened. However, during movement from the open to the closed circuit position, segments 127 of the auxiliary switch 81 will have passed over the terminals *e-f* so as to close the circuit to the coil 91 of the pilot valve 79. Thus when the pilot valve 79 is open, compressed air from the tank 5 is admitted through the pipe 65 to the upper end of the control valve 63, thereby opening the control valve 63 to permit air to pass through the conduit 67, manifold 69 and the passages 71 to the arc extinguishing units 21 where it is directed in a blast between the respective contacts 23 and 25. Thus should a spark jump between the contacts during the closing operation, a blast of air is available to quickly extinguish the arc.

It should also be noted that the operating cylinder 47 is provided with a latch 135 adapted to engage a suitable notch 137 formed in the operating rod 43 when the moving contact struc-

ture is in the closed circuit position. The latch 135 and notch 137 forms a locking means for positively mechanically holding the contacts in closed position against any force applied to the contacts acting in a direction to open the contacts.

If it is desired to open the interrupter by manual control, the bottom 139 of the push-button switch 111 is depressed so as to connect the line 93 of the control potential source through conductor 109, to conductor 107, conductor 99, to the terminals *a-b* of the auxiliary switch 81 which, for this position of the interrupter are bridged by the segments 123 and thus complete the circuit to the conductor 97 which, in turn, is connected to the coil 87 of the pilot valve 75. Since the other terminal of the coil 87 is permanently connected by the conductor 95 to the line 92 of the potential source, the circuit through the potential source of the control system is completed and the coil 87 is energized. Energization of the coil 87 causes pilot valve 75 to be opened, thereby admitting air from the pressure tank 5 through the conduits 53 to the upper end of control valve 51 which causes air under pressure to be admitted through conduit 55 to the operating cylinder 47. Air from the conduit 57 does not pass directly to the piston chamber within the operating cylinder 47 but is directed to a valve chamber 141 which has access to the upper side of the piston 45 through a valve 143. Valve 143 is biased to the closed position by a spring 145 which may be pretensioned so that the valve 143 will not open to admit air to the piston 45 unless the pressure in the tank 5 is sufficient to promptly move the piston 45 to the open circuit position and to deliver a blast of compressed air sufficient to extinguish the arcs in the circuit interrupting units 21.

Assuming that the air pressure is sufficient to permit prompt movement of the contact structure and also extinction of the arcs, the valve 143 is raised permitting air to flow to the upper side of the piston 145 which tends to urge the piston downwardly in a direction to move the moving contact structure to the open circuit position. This movement, however, will not take place immediately since the operating rod 43 is latched in the closed circuit position by the latching member 135 engaging the notch 137. The valve 143, however, is coupled by a link 147 to the latching lever 135 so that following a predetermined movement of the valve 143, the latch 135 will release the operating rod 43 to permit the contact structure to be moved to the open circuit position. It is apparent, from the fact that the valve 143 is connected to the latch 135, that the latch or holding means 135 will begin to move and overcome its static friction as soon as the valve 143 begins to move, and continues to move while the gas is flowing from the valve 143 to the upper side of piston 45. This movement of the holding means begins before appreciable force is applied to the moving contact tending to move it open, so that the static friction of the holding means which has to be overcome is much smaller than if opening force were applied to the moving contact prior to or at the same time as the beginning of the releasing movement of the holding means. It will also be seen that a certain amount of time delay is obtained between the initial opening of the valve 143 and the final release of the latch 135. The amount of time delay that is desirable depends upon the time required to substantially build up full operating pressure above the piston 45 prior to final release of the latch 135. Under

these conditions, final release of the latch 135 causes a rapid opening movement of the moving contacts which in effect takes place with a snap action.

It is also seen that in the event the pressure in the tank 5 is insufficient to open the valve 143 or is insufficient to raise the valve 143 an amount necessary to unlatch the operating rod 43, the moving contact structure of the interrupter remains in the closed circuit position. Thus the auxiliary control switch 81 also remains in the closed circuit position and the electromagnet 91 of the pilot valve 79 remains deenergized so as not to further deplete the supply of gas stored in the pressure tank 5.

Under the conditions where sufficient pressure exists in the tank 5 to permit opening of the interrupter, immediately following initial movement of the contacts 25 toward the open circuit position, the terminals *e-f* of the auxiliary switch 81 are bridged by the segments 127 so as to energize the coil 91 of the pilot valve 79 which, in turn, opens the control valve 63 to admit a blast of arc extinguishing gas to each of the circuit interrupting units 21. Upon reaching the full open circuit position, the auxiliary switch will take the position, as shown in Fig. 4, to break the bridging relation between the terminal contacts *a-b* so as to deenergize the coil 87 of the pilot valve 75.

It will be understood that push-button switch 111 may be of any well known type used for the remote control of the electrical apparatus but preferably is of the type which assumes a neutral position following the completion of the switching operation initially controlled by operation thereof. In order to indicate the position of the circuit interrupter at a remote point, we provide signal lamps 149 and 151 which are controlled by the segments 129 and 131 of the auxiliary switch 81. For example, indicating lamp 149 preferably shows a red signal when the breaker is in the closed circuit position, whereas the lamp 151 is energized and shows a green signal when the breaker is in the open circuit position. The specific method of connecting the signal lamps 149 and 151 to the control potential source 92 and 93 is well known in the art and need not be further described.

In the event that it is desired to trip or to open the circuit interrupter automatically, as for instance, in response to an overload or fault occurring in the circuit in which the interrupter is connected, we provide a trip coil circuit (not shown) which is connected to the coil 153 of the relay 105. Upon energization of the coil 153 in response to an overload, the relay 105 closes a circuit from the line 93 through the conductor 103, and 101 to the conductor 99 which is in circuit with the terminals *a-b* of the auxiliary switch 81 which, in turn, completes the circuit through the conductor 97 to the coil 87 of the pilot valve 75, which coil is energized as a result of being connected to the line 92 of the control potential source by the conductor 95. Energization of the coil 87 causes actuation of the pilot valve 75 in the manner previously described so as to effect operation of the contact structure to the open circuit position as well as to cause an arc extinguishing blast of gas to flow between the separating contacts and extinguish the arcs.

It will be understood that suitable circuit connections can be made to the conductor 115 for automatically reclosing the circuit interrupter. It will also be apparent that if upon closing the

circuit interrupter at such time when an overload or fault condition exists on the connected circuit, relay 105 will be immediately energized to bring about opening of the interrupter in the manner previously described.

Although we have shown and described a specific circuit interrupting structure and control means therefor, it is to be understood that the same was for the purpose of illustration and that changes and modifications may be made by those skilled in the art without departing from the spirit and scope of the appended claims.

We claim as our invention:

1. In a gas blast circuit breaker, separable contacts for establishing an arc, a source of gas under pressure, means for directing a blast of gas from said source against the arc to extinguish the arc, operating means actuated by gas under pressure from said source for moving said contacts to closed position, means for positively mechanically holding said contacts in the closed position, and said holding means being operated mechanically by the pressure of said source for releasing said contact means to move to open position with the pressure from said source for releasing the holding means applied prior to the application of force to the moving contact tending to move it in opening direction.

2. In a gas blast circuit breaker, separable contacts for establishing an arc, a source of gas under pressure, a piston actuated by gas under pressure from said source for moving said contacts to open and closed positions, means for holding said contacts in the closed position, a valve for admitting gas under pressure from said source to said piston to operate said contacts to open circuit position, and pressure responsive means disposed between said valve and said piston operative to release said holding means and admit gas to said piston only upon the delivery of gas by said valve of predetermined pressure.

3. In a gas blast circuit breaker, separable contacts for establishing an arc, a source of gas under pressure, a piston actuated by gas under pressure from said source for moving said contacts to open and closed positions, means for latching said contacts in the closed position, a valve for admitting gas under pressure from said source to said piston to operate said contacts to open circuit position, a valve member disposed between said valve and said piston movable to open and closed positions for controlling the flow of gas to said piston, resilient means biasing said valve member to the closed position, said resilient means enabling said valve member to open in response to a flow of gas from said valve of predetermined pressure, and means operable in response to movement of said valve member to the open position for releasing said latching means to enable said piston to move said contacts to the open circuit position.

4. In a gas blast circuit breaker, separable contacts for establishing an arc, a source of gas under pressure, a piston actuated by gas under pressure from said source for moving said contacts to open and closed positions, means for latching said contacts in the closed position, a valve for admitting gas under pressure from said source to said piston to operate said contacts to open circuit position, and a pressure responsive member disposed between said valve and said piston operative in response to gas at a predetermined pressure from said source to admit gas to said piston and to release said latching means, said pressure responsive member delaying release of

said latching means until substantially full operating pressure is available at said piston to cause said piston to open said contacts with a snap action.

5. In a gas blast circuit breaker, circuit interrupting means including a moving contact structure, a fluid pressure actuated piston for moving said contact structure to open and closed positions, a source of gas under pressure, a control valve arranged to admit gas under pressure from said source to said piston to operate said contact structure to open circuit position, a gas blast valve arranged to admit an arc extinguishing blast from said source to said circuit interrupting means, electromagnetic means for controlling said valves, means for energizing said control means for operating said control and gas blast valves in the order named, means for positively mechanically holding said contact structure in the closed position, and pressure responsive means for releasing said holding means only when sufficient pressure exists at said source to extinguish the arc.

6. In a gas blast circuit breaker, circuit interrupting means including a moving contact structure, a fluid pressure actuated piston for moving said contact structure to open and closed positions, a source of gas under pressure, means directing an arc-extinguishing blast from said source to said circuit interrupting means, a control valve operative to admit gas under pressure from said source to said piston to operate said contact structure to the open circuit position, a pressure responsive valve between said control valve and said piston for controlling the flow of gas to said piston, and means holding said contact structure in the closed position against movement to the open position until a predetermined pressure is available at said piston.

7. In a gas blast circuit breaker, circuit interrupting means including a moving contact structure, a fluid pressure actuated piston for moving said contact structure to open and closed positions, a source of gas under pressure, means directing an arc-extinguishing blast from said source to said circuit interrupting means, a control valve operative to admit gas under pressure from said source to said piston to operate said contact structure to the open circuit position, a pressure responsive valve between said control valve and said piston for controlling the flow of gas to said piston, latch means for normally holding said contact structure in the closed position against movement to the open position, and means actuated by said pressure responsive valve for releasing said latch means only when substantially full operating pressure is available at said piston to cause said piston to open said contact structure with a snap action.

8. In a circuit interrupter of the gas blast type, a reservoir for storing gas under pressure arranged to be maintained at ground potential, an arc-extinguishing device including separable contacts, at least one of which is movable, means at least partially of insulating material for insulatingly supporting said arc-extinguishing device with respect to said reservoir, said support means including a tubular insulator, means including said tubular insulator for conducting an arc-extinguishing blast of gas from said reservoir to said arc-extinguishing device, and a conducting support for said movable contact carried by said tubular insulator intermediate its ends and arranged to permit movement of said movable con-

tact with respect thereto and with respect to said arc-extinguishing device.

9. In a gas blast circuit interrupter, a base structure including a tank at ground potential for storing gas under pressure, separable contacts, an arc chamber in which said contacts separate to establish the arc, means for insulating and supporting said arc chamber from said base structure and tank including a conduit of insulating material for conducting gas from said tank to said arc chamber, a piston mounted at ground potential on said base structure and tank, an insulated operating rod extending from said piston to actuate said contacts, and control means also supported on said base structure and tank at ground potential for controlling the flow of gas to said arc chamber and said piston.

10. In a gas blast circuit interrupter, a base at ground potential, supporting means of insulating material extending from said base; an arc chute, a contact and a terminal for the circuit interrupter connected to said contact all carried by said supporting means of insulating material and insulated from the base thereby; a second terminal for the circuit interrupter mounted on said supporting means of insulating material and insulated thereby both from said base and from the first said contact and terminal, a movable contact connected to said second terminal and engageable with the first said contact, and operating means at ground potential connected by means of insulating material to the movable contact, said operating means moving said movable contact through the arc chute from a position in engagement with the first said contact to a position out of the arc chute where there is a visible gap between the movable contact and the arc chute.

11. In a circuit interrupter, separable contacts for establishing an arc, a source of gas under pressure, operating means actuated by gas under pressure from said source for moving said contacts to closed position, mechanical means for rigidly holding said contacts in the closed position, and means operated by gas pressure applied thereto from said source prior to the application of force to said contacts tending to separate them for mechanically releasing said holding means and permitting movement of the contacts to open position.

12. In a circuit interrupter, separable contacts for establishing an arc, a source of gas under pressure, operating means including a piston actuated by gas under pressure from said source for moving said contacts to closed position when pressure is applied to one side of said piston and for moving said contacts to open position when pressure is applied to the other side of said piston, mechanical means operable automatically upon said contacts reaching closed position for rigidly holding said contacts in the closed position against any force applied to the contacts tending to move them to open position, and means operated by the gas pressure admitted from said source to the opening side of the piston for automatically mechanically releasing said holding means and permitting movement of the contacts to open position by the gas pressure admitted to the opening side of the piston, and said means acting to begin the release of the holding means prior to the application of force to the contacts tending to move them in the opening direction.
